METHOD OF PURIFYING ANTHRAQUINONE.

Application filed January 27, 1922. Serial No. 532,099.

This invention relates to an improved method of subliming and purifying substances that are sublimable with steam, and more particularly to the purification of anthraquinone whereby the anthraquinone can be obtained in a state of high purity.

According to the present invention, the crude anthraquinone is subjected to sublimation with superheated steam, and the vapors of anthraquinone and other volatile or sublimable constituents are subjected to a regulated cooling operation by passing the vapors first through a hot condenser, maintained at a regulated temperature, and then through a relatively cold condenser at a low temperature. The process is carried out with utilization of the superheated steam in a particularly advantageous manner.

Among the advantages which the invention presents may be mentioned the absence of danger of explosion, the ease of regulation of the temperature, the economy in the utilization of the steam, and the avoidance of the necessity of direct heating of the sublimer by a direct flame or by products of combustion.

The sublimation of the anthraquinone is effected by heating the anthraquinone both indirectly by means of a steam jacket and directly by means of the superheated steam which also promotes the sublimation. The steam can advantageously be utilized first at a higher temperature in the steam jacket and then directly in the sublimer, with regulation of the amount and temperature of the steam to obtain the desired heating effect.

The condensation of the sublimate is carried out in successive stages, first at an elevated temperature of about 175-275° C., and later at a low temperature such that the steam itself will condense with the remaining impurities. The first or hot condenser may be preliminarily heated by steam in a steam jacket, but after it has once been heated, the further supply of heat will be often unnecessary as the superheated steam and the sublimate will serve to keep the condenser hot, and in fact, it may be necessary to cool the condenser to a sufficient degree to maintain it within the proper temperature limits for the desired hot condensation. The amount of heat which is thus made available in the cooling of the superheated steam and in the condensation of the anthra-

quinone is such that often it can be utilized to advantage in preheating the steam or a part of the steam for the sublimation. For example, the condenser may have a steam jacket through which the steam is circulated to cool the condenser, and with resulting increase in the temperature of the steam circulating through the jacket. By a proper counterflow circulation, the steam in the jacket can be raised to a temperature approximating that of the steam entering with the sublimate. This preheated steam may then be used in the sublimer, with such additional superheating as may be necessary, or it may be admixed with the superheated steam at a higher temperature from the jacket of the sublimer and the resulting superheated steam then used in the sublimer.

In the hot condenser, maintained within proper temperature limits, the anthraquinone can be condensed without the condensation of impurities present in the vapor phase and which condense at a lower temperature. The vapor pressure of anthraquinone in the presence of superheated steam at a temperature between about 175 and 275° C. is very much less than the vapor pressure of the volatile impurities commonly found in crude anthraquinone manufactured, for example, by oxidizing anthracene with a solution of chromic acid or other oxidizing agent, or by the catalytic vapor phase oxidation of anthracene, or by the synthetic process from benzene and aluminum chloride, etc.

After the mixture, in the vapor phase, of superheated steam and anthraquinone, with its impurities, has passed through the hot condenser, and the anthraquinone condensed with substantial completeness, the resulting vapors are then passed to a cold condenser maintained at about ordinary room temperatures or at temperatures below the condensation temperature of the steam, so that complete condensation will take place of all the remaining vaporized constituents and including the steam itself. The handling of residual gases is thus avoided, while the completion of the condensation is facilitated.

Instead of passing the superheated steam and impurities directly to a cold condenser from the hot condenser, they may be passed through a condenser or condensers maintained at intermediate temperatures to bring

about a further fractional condensation of impurities.

The invention will be further described in connection with the accompanying drawing illustrating in a somewhat conventional and diagrammatic manner one form of apparatus embodying the invention and adapted for the practice of the process of the invention, the apparatus being illustrated in vertical section and with parts in elevation.

Referring to the accompanying drawing, the sublimer is indicated at 1 and is provided with a steam jacket 2 and a supplemental steam jacket 3 at its upper end. The sublimer communicates through the pipe 4 with the hot condenser 5 having a steam jacket 6 and this in turn communicates through the pipe 7 with the cold condenser 8, provided with a cooling jacket 9. A suitable superheater 10 is provided for superheating steam to the necessary temperature, the superheater being heated by gas burners 11 or by other suitable heating means. The steam, which may be supplied through pipe 26, enters the superheater at 12 and passes out through the pipe 13 which has a branch pipe 14 leading to the top of the steam jacket 3 from which the steam passes through the pipe 15 to the steam jacket 2 and thence through the pipe 17 to the inside of the sublimer where it is admitted near the bottom of the sublimer through openings in the end of pipe 18. A branch connection 19 permits the superheated steam to enter the jacket 6 of the hot condenser to preheat it at the beginning of the process. A separate steam supply 20 is provided for admitting steam at a lower temperature to cool the hot condenser during the process. This steam is introduced at a temperature sufficiently low to cool the condenser to the desired temperature, and it will be heated to a higher temperature before it escapes at 21. The steam thus further preheated in the jacket 6 may be passed to the superheater through the pipe 22 to be further superheated, or it may be to a greater or less extent passed into the sublimer through the branch pipe 23 in admixture with highly superheated steam from the superheater in which case a portion of the steam to the superheater may be supplied from pipe 26. Any excess of steam from steam jacket 6 can be discharged through pipe 25. Pipe 27 is a drain-pipe for the steam jacket of the sublimer and pipe 28 is similarly a drain-pipe for the steam jacket of the hot condenser. Water condensed in these jackets on starting the apparatus from the cold is advantageously drawn off through the drain-pipes 27 and 28.

The cold condenser 8 may have water circulated through its jackets to cool it to a temperature sufficient to complete the condensation of the vapors, and it may have a

filter cloth at its outer end, as indicated at 24 to prevent escape of any of the condensate therethrough other than the condensed steam.

The sublimer 1 will in practice be provided with a suitable charging opening at its top and a discharge opening at its bottom for the residue. The hot condenser will similarly be provided with a discharge opening at its lower end and may have scraping devices for scraping the condensate from the walls of the chamber. It will be understood that suitable thermometers or pyrometers are provided for indicating the temperature so that it may be maintained within proper limits.

The operation of the apparatus and the practice of the process therein will be further illustrated by the following specific example. The impure anthraquinone resulting, for example, from the oxidation of anthracene with chromic acid, is charged into the sublimer and heated therein, by the circulation of highly superheated steam through the jacket and through the anthraquinone itself, to a temperature of about 275 to 350° C. The same steam utilized at a higher temperature in the jacket is advantageously used at a somewhat lower temperature in the sublimer. The vapor pressure of the anthraquinone and of the volatile impurities present in the crude anthraquinone is such, in the presence of superheated steam, that both the anthraquinone and its volatile impurities are sublimed and pass over with the steam into the condenser 5, which is kept at a temperature of from 175 to 275° C. or, in some cases, it may be kept within a narrower temperature range of, for example, 180 to 190° C. At such temperatures, substantially none of the steam is condensed while the anthraquinone is readily condensed without any considerable condensation of impurities, inasmuch as the vapor pressure of anthraquinone in the presence of steam between 175 and 275° C. is much less than the vapor pressure of the volatile impurities commonly present in the crude anthraquinone. The impurities accordingly will remain chiefly in the vapor phase and will pass out of the hot condenser 5 into the condenser 8 which is maintained at a temperature preferably below that of the condensation of steam and in which the steam will be condensed along with the impurities, and the condensation of the steam will assist in the complete condensation of the other materials, which will thus be obtained in a moist state.

The anthraquinone produced in the manner above described is substantially pure and can be obtained in the form of yellow needle-like crystals free from such impurities as anthracene, and acenaphthene and carbazol and their oxidation products, etc., and with a melting point above 285.2° C.

In the carrying out of the process I regard it as important to have a sharp temperature gradient between the hot condenser and the cold condenser, and to run a relatively rapid current of the vapors through the apparatus, while maintaining proper temperature control, so that the anthraquinone will be deposited in the hot condenser in a substantially pure state, and the anthracene and other impurities in the cold condenser which is maintained at a considerably lower temperature.

The purification of substances other than anthraquinone may be carried out in a similar manner, but the conditions of operation will differ somewhat in each case. For example, the process of the present invention may be used in a similar way and to similar advantage in the purification of other quinones or their derivatives, for example phenanthraquinone, methylanthraquinone, aminoanthraquinone, benzanthrone, etc. It is also applicable to the purification of many hydrocarbons and their derivatives, for example, anthracene, phenanthrene, carbazole, etc.

I claim:

1. The method of purifying crude anthraquinone which comprises heating anthraquinone to temperatures between 275 and 350° C. by circulating superheated steam in indirect contact therewith and then into direct contact therewith to bring about its sublimation, and cooling the resulting vapors first at an elevated temperature to separate anthraquinone therefrom and subsequently the remaining vapors at a lower temperature to separate other constituents.

2. The method of purifying crude anthraquinone which comprises heating anthraquinone to a temperature of about 275°-350° C. by circulating superheated steam in indirect contact therewith and then into direct contact therewith to bring about its vaporization, and cooling the resulting vapors first to a temperature of about 175°-275° C. to separate anthraquinone therefrom, and then the remaining vapors to a temperature below the boiling point of water to separate other constituents therefrom.

In testimony whereof I affix my signature.
HARRY F. LEWIS.
